(57) **CLAIM**

The ornamental design for a double headed tweezers, as shown and described.

DESCRIPTION

FIG. 1 is a perspective view of the double headed tweezers showing my new design;

FIG. 2 is an top view of the double headed tweezers thereof;
FIG. 3 is a side view of the double headed tweezers thereof;
FIG. 4 is a bottom view of the double headed tweezers thereof;

FIG. 5 is a left end view of the double headed tweezers thereof; and,

FIG. 6 is a right end view of the double headed tweezers thereof.

The broken lines immediately adjacent the shaded areas represent the bounds of the claim and all other broken lines are for illustrative purposes only. None of the broken lines form a part of the claimed design.
